(57) **CLAIM**

The ornamental design for a mini vehicle set, as shown and described.

DESCRIPTION

FIG. 1 is a perspective view of a mini vehicle set, comprising a remote control and a mini vehicle, showing the remote control separately for complete disclosure;

FIG. 2 is another perspective view of the remote control thereof;

FIG. 3 is a front elevational view of the remote control thereof;

FIG. 4 is a rear elevational view of the remote control thereof;

FIG. 5 is a left side view of the remote control thereof;

FIG. 6 is a right side view of the remote control thereof;

FIG. 7 is a top plan view of the remote control thereof;

FIG. 8 is a bottom plan view of the remote control thereof;

FIG. 9 is a partial enlarged view of FIG. 1 thereof;

FIG. 10 is a perspective view of a mini vehicle set, showing the mini vehicle separately for complete disclosure;

FIG. 11 is another perspective view of the mini vehicle set thereof;

FIG. 12 is a front elevational view of the mini vehicle set thereof;

FIG. 13 is a rear elevational view of the mini vehicle set thereof;

FIG. 14 is a left side view of the mini vehicle set thereof;

FIG. 15 is a right side view of the mini vehicle set thereof;

FIG. 16 is a top plan view of the mini vehicle set thereof;

FIG. 17 is a bottom plan view of the mini vehicle set thereof;

FIG. 18 is a partial enlarged view of FIG. 10 thereof; and,

FIG. 19 is an assembled view of the mini vehicle set thereof.

The evenly dashed broken lines depict portions of the mini vehicle set that form no part of the claim. The long-short dash lines depict the bounds and indicia for magnified portions and form no part of the claim.

1 Claim, 19 Drawing Sheets
